UNITED STATES PATENT OFFICE.

ERNEST W. WEINMANN, OF CHICAGO, ILLINOIS.

METHOD OF REMOVING BATTERY-TERMINALS.

1,265,980.

Specification of Letters Patent. Patented May 14, 1918.

Application filed December 8, 1916. Serial No. 135,870.

To all whom it may concern:

Be it known that I, ERNEST W. WEINMANN, a citizen of the United States, residing at Chicago, in the county of Cook and State of Illinois, have invented certain new and useful Improvements in Methods of Removing Battery-Terminals, of which the following is a specification.

The common method of making storage batteries is to assemble all of the parts with the groups in place, and these groups have upwardly extending posts which project through the covers. These covers are sealed in position, and then the terminals are applied to the posts and are burned on so as to make a substantially integral connection. When it becomes necessary to take the battery apart for inspection or repairs, the usual practice is to burn off the terminals or else bore a hole through the same of substantially the same diameter as the post. In either event, when the terminal is removed, the original post is entirely cut away, leaving nothing projecting to any appreciable distance above the top of the battery cover. It is then necessary to remove the cover, which is commonly done by taking out the sealing compound with a hot putty knife or other suitable instrument, but in doing this, the case cover is apt to be broken. After the cover is removed, the stubs of the original posts may be reached for withdrawing the groups. In reassembling the parts, it is difficult to burn on a new terminal to these stubs, as they project but slightly from the top of the box, and dirt or other impurities are apt to interfere with the burning, so as to make a poor connection. Such dirt or impurities is apt to cause high resistance, which frequently generates sufficient heat to burn off the terminals.

In accordance with the present invention I provide a method of removing battery terminals, which not only removes the terminals in an easy and convenient manner, but leaves posts similar to the posts with which the groups were originally supplied.

The objects of the present invention are to provide a simple and convenient method for removing battery terminals, which may be readily practised by even unskilled persons; to provide a method for removing battery terminals, which will leave posts for making a new connection; and to provide

such an improved method as will be more fully described hereinafter.

In the accompanying drawings illustrating a preferred way of carrying out my improved method;

Figure 1 is a plan view of the top of a storage battery or the like;

Fig. 2 is an enlarged view taken on the line 2—2 of Fig. 1; showing a cross section of the terminal, which has been burned onto the original post to form a unitary structure;

Fig. 3 illustrates the method of boring or cutting an annular groove in the terminal for removing the terminal while leaving a post; and

Fig. 4 indicates the post which is left after the terminal is removed, the terminal being indicated in dotted lines.

In the carrying out of this process I prefer to utilize a boring tool such as shown in my co-pending application, which will bore an annular groove or channel. When it is desired to remove a terminal, the operator centers the tool on the terminal 5, as shown in Fig. 1, and then actuates the same to bore an annular groove 6. The outer diameter of this groove is preferably about the same as the outer diameter of the post or connection member 7, while its inner diameter is sufficient to leave a substantial core 8. When the end of the tool passes through the terminal, as indicated in Fig. 4, the terminal may be removed and the core 8 then provides a projection or post similar to the original post of the battery.

It will be seen that my improved method provides an easy and advantageous way of removing the terminal, which may be practised by anyone even having little or no skill in such matters. Furthermore, the leaving of the post or core 8 extending above the cover provides something for the operator to get hold of, so that the group may be pulled out with but slight heating of the sealing compound, so that the cover will come off with the group. Furthermore, the projecting post furnishes a connection for charging the battery before it is again rebuilt, as this is often done. Temporary terminals may be connected to these posts for supplying current to the groups.

This solid post is also of advantage in reassembling the battery, as it gives a post similar to the one originally provided when

the battery was first assembled. This saves time in burning on a new terminal, and also prevents the liability of making a poor connection, as is apt to be done with the old 5 method.

It will thus be seen that my improved method not only contemplates the removal of the terminals, but also provides means for readily removing the groups from the 10 battery, and also provides for the convenient reassembling of the battery and connecting new terminals therewith.

Having thus described my invention, which, however, I do not wish to limit to 15 the exact steps herein shown and described, except as specified in the following claims, what I claim and desire to secure by Letters Patent is:

1. The method of removing a battery terminal which consists in forming an annular groove through the terminal, concentric with the original battery post or connection.

2. The method of removing a battery terminal which consists in forming an annular groove through the terminal, of substantially the same outer diameter as the adjacent portion of the post or connection, and having an internal diameter sufficiently large to leave a substantial projection from 30 said post or connection.

3. The method of disassembling and assem-

bling batteries which consists in boring an-
nular holes through the terminals for re-
moving them while leaving projecting posts,
then removing the groups by raising the 35
same with the covers thereon from the jars,
and then reassembling the battery parts by
inserting the groups with the covers there-
on, and finally burning other terminals onto
said posts or projections. 40

4. The method of removing connectors from the terminal posts of storage battery electrodes, which consists in cutting an an-
nular groove through the metal uniting the 45
connector and post, with the groove enter-
ing through the top of the connector and
extended to a depth to be below the fused
union between the connector and post.

5. The method of removing and replacing
connectors from the terminal posts of stor- 50
age battery electrodes, which consists in cut-
ting an annular groove through the metal
uniting the connector and post, with the
groove entering through the top of the con-
nector and extended to a depth to be below 55
the fused union between the connector and
post, and on replacing the connector after
its removal from the post filling the groove
with lead and causing its integral union
with the walls of the groove by burning.

ERNEST W. WEINMANN.
